CLAIM

The ornamental design for a trim for recessed lighting fixture or the like, as shown and described.

DESCRIPTION

FIG. 1 is a perspective view of a trim for recessed lighting fixture or the like showing my new design;

FIG. 2 is a top plan view thereof on an enlarged scale;

FIG. 3 is a front elevational view thereof on an enlarged scale, the rear and sides being identical; and,

FIG. 4 is a bottom plan view thereof on an enlarged scale.

*FIG. 1**FIG. 2**FIG. 3**FIG. 4*
